CAMPER UNIT FOR PICK-UP TRUCKS OR THE LIKE

Allen P. Baumer, 1007 Monroe St.,
Saginaw, Mich. 48602

Filed Apr. 15, 1974, Ser. No. 460,705

Term of patent 14 years

Int. Cl. D12—16

U.S. Cl. D12—156

FIG.1

FIG.6

FIG. 1 is a perspective view of a camper unit for pick-up trucks or the like showing my new design;

FIG. 2 is an enlarged, top plan view thereof;

FIG. 3 is an enlarged side elevational view thereof, the opposite side being a mirror image of the side shown herein;

FIG. 4 is an enlarged bottom plan view thereof;

FIG. 5 is an enlarged rear elevational view thereof; and

FIG. 6 is an enlarged front elevational view thereof.

I claim:

The ornamental design for a camper unit for pick-up trucks or the like, as shown.
